(57) CLAIM

The ornamental design of a container for cosmetic products, as shown and described.

DESCRIPTION

FIG. 1 is a perspective view of a decorative container for cosmetic products;

FIG. 2 is a front elevational view of the decorative container for cosmetic products;

FIG. 3 is a left side view of the decorative container for cosmetic products, the right side view being a duplicate thereof;

FIG. 4 is a rear elevational view of the decorative container for cosmetic products;

FIG. 5 is a top plan view of the decorative container for cosmetic products; and,

FIG. 6 is a bottom view of the decorative container for cosmetic products.

The broken lines of the head are for illustrative purposes only and form no part of the claimed design.
